Patented Dec. 28, 1915.

UNITED STATES PATENT OFFICE.

THEODOR EUGEN BUSCHMANN, OF CHEMNITZ, GERMANY, ASSIGNOR TO THE FIRM OF WANDERER WERKE VORM. WINKLHOFER & JAENICKE AKT.-GES., OF SCHÖNAU, NEAR CHEMNITZ, GERMANY.

TYPE-WRITER RIBBON-SHIFT.

1,165,942.

Specification of Letters Patent. Patented Dec. 28, 1915.

Application filed November 22, 1913. Serial No. 802,577.

To all whom it may concern:

Be it known that I, THEODOR EUGEN BUSCHMANN, a subject of the Emperor of Germany, residing at Chemnitz, Saxony, Germany, have invented certain new and useful Improvements in Type-Writer Ribbon-Shifts, of which the following is a specification.

This invention relates to devices for shifting the ribbon of typewriting machines.

The object of the invention is to provide for a lifting of the ribbon with a variable stroke, in order to render possible the proper working of letters or signs which happen to be situated or placed especially high on the type as compared with the other letters or signs. For letters or signs of this character, and which occur for instance in Sanskrit type, an increased lifting movement of the ribbon at right angles to its longitudinal direction is necessary, because, by the normal lifting movement with the normal width of the ribbon, the letters situated especially high are not printed. The ribbon must therefore receive an additional lifting movement, which must be sufficient, when using the normal width of the ribbon, to raise said ribbon so high that the letters situated in the high position are also printed. The apparatus according to this invention is, however, when using bichrome ribbons, also capable of allowing certain signs or letters to appear in a different color. This is effected when typing these signs, by automatically imparting an additional movement to the ribbon, which is sufficient to bring the other colored part of the band into the printing line of the sign in question.

This invention is illustrated by way of example in the accompanying drawings, in which:—

Figure 1 is a side elevation of the ribbon lifting apparatus, and indicates its position relatively to the frame of the typewriting machine. Fig. 2 is a corresponding view of certain parts in a different working position. Fig. 3 shows diagrammatically three different positions of the ribbon relatively to the signs or letters.

The shift frame 1, on the bent rail of which the platen is guided in a known way, can be raised for shifting in order to print an alternative sign or letter, by means of

the arm 2 and the intermediate member 3 which are influenced by the shift key 4. A key lever 5 sets the type lever 7 in motion by means of the intermediate member 6, so that the type mounted in the end of the lever is raised and caused to strike against the platen. The key levers 5 act also in the known manner on the universal bar 8, which is secured to a member 9, pivotally mounted on a pin 10. On the pin 10 a lever arm 11 is so situated, that it coöperates with levers 12 and 12^a of a bell crank lever 14 mounted on the rock shaft 13. A bar 15 is linked on the upper arm of the bell crank lever 14, and the end of said bar 15 is also pivotally connected with a lever 17, which latter is mounted on the pin 16 on a projection of the shift frame 1, and drives the ribbon guide 18. The bar 15 is provided with a stop 19 adjustable by means of slots and screws, and also with a stationary stop 20. These two stops 19 and 20 are designed to co-operate with the bent stop 22^a of the stopping member 22, which is secured upon a locking pin 21 of the shift frame 1. The stopping member 22 is under the action of a tension spring 23, which has a constant tendency to hold the striking member 22 in the position shown in Fig. 1. A pin 27 is secured to the intermediate member 6, which pin is arranged within a curved slot, 85 provided at one end of a tension bar 24. The other end of this bar is connected by means of a slot 30 and a pin 28 to a lever 29 arranged on the rock shaft 13. On the tension bar 24 is also situated a striking pin 25, which is adapted to coöperate with a lever arm 22^b secured to the rocking axle 21. The above described devices are situated only on the intermediate members of the corresponding parts for those type levers which carry signs or letters in an especially high position.

The operation is as follows:—When typing normal letters or letters which do not require a special lifting movement of the ribbon on account of the letters or signs being situated in a high position on the type, the key lever 5 is pressed down in the usual manner and the different parts take the position shown in Fig. 1 in dotted lines, 105 the type lever 7 being in its striking position. In this case the ribbon is brought into the printing position for the lower case let-

ters or signs of the type corresponding to Fig. 3 Sketch I. If the upper case signs or letters are to be printed, then the lifting of the platen and the ribbon into the upper 5 position shown in Fig. 3 Sketch II, must take place in the known manner by pressing on the shift lever 4. If, however, the upper signs or letters are situated especially high as is shown in Fig. 3 then according to 10 Sketch II, the uppermost part of the letter or sign would not be printed. The ribbon and platen must have therefore an additional movement, so that it can assume the position shown in Fig. 3 Sketch III above 15 upper case position, in order also to print the uppermost part of the high letters or signs. When the shifting of the platen has been performed and the key lever is pressed, which corresponds to a type with unusually 20 high letters or signs, then, because the tension bar 24 is arranged on the corresponding intermediate lever 6, said tension bar 24 projecting through a slot of the shifting frame 1, the front end is lifted and brought 25 into the position shown in Fig. 2. The curved slot 26 of the tension bar 24 slides relatively to the pin 27 and, on account of its formation, draws the tension bar 24 to the right, whereby the lever 29 is rocked to 30 the right, and also the lever 14, and therefore by means of this lever and the co-operation of the rod 15, also the lever 17 35 engaging the ribbon guide 18 and therewith the ribbon guide 18 itself, receive an additional movement. In the position shown in Fig. 2, the striking pin 25 on the tension bar 24 strikes against the lever arm 22^b and rotates thereby the rocking pin 21 in a counter clockwise direction, so that the bent 40 stop 22^a is moved from out of the path of the stop 20 and the rod 15 can then perform an additional movement until the movable stop 19 (Fig. 2) strikes against stop 22^c. These stops 20 and 19 must be present in 45 order that the ribbon cannot be thrown too high. The lever arm 22^b is provided with a sloping surface at its lower end, which permits the pin 25 to slide upward and assume a position to the left in front of the lever 50 arm 22^b, should it accidentally come beneath the end of the lever arm 22^b (as illustrated in dotted lines Fig. 1). The additional stroke of the ribbon guide can be regulated by means of the adjustable arrangement of the stop 19.

It is clear that in all type and key lever arrangements, which are fitted with the above described apparatus, the ribbon can be raised to the height of the uppermost letter 60 or sign as shown in Fig. 3 Sketch III by means of the additional movement, and that these unusually high letters or signs will be also printed. Further it will be easily understood that the apparatus may also be 65 used for typing higher letters or signs in

a different color, if a bi-chrome ribbon is used. When this is the case, the additional movement may cause for instance, the red part to reach the printing position for the upper letters or signs.

Finally, it must be remarked that the apparatus according to this invention may be used for typewriting machines having a ribbon vibrator actuated from the universal bar and having this bar actuated by the 75 notched rear ends of the key levers.

I claim:—

1. In a typewriting machine, the combination with a type lever and a ribbon mechanism normally vibrating between a position of rest and normal printing position; of means to automatically cause the ribbon mechanism to move beyond normal printing position upon the actuation of a particular type lever whose type printing position is 80 beyond the normal printing line.

2. In a typewriting machine the combination with a platen and a platen shifting mechanism to control the position of the platen; of a ribbon shifting mechanism 90 operating normally between its position of rest and the printing position, and a type lever mechanism including means to shift the ribbon an additional distance, said means controlled from the platen shifting 95 mechanism.

3. In a typewriting machine, a ribbon shifting mechanism having a stop to normally control the movement of said mechanism between a position of rest and its printing position, a pivoted stop coöoperating with the aforementioned stop, an adjustable stop, key lever actuated means to automatically move the pivoted stop into the path of the adjustable stop to permit said mechanism to have a movement greater than its 100 normal movement.

4. In a typewriting machine, a ribbon shifting mechanism normally operating between a position of rest and the normal printing position, and means to automatically cause the shifting of said mechanism beyond said printing position upon the actuation of a key lever and including means to adjust the extent of said additional movement.

5. In a typewriting machine, a ribbon shifting mechanism including a reciprocable member having a fixed stop and an adjustable stop, in combination with a pivoted stop arranged to coöperate with either of the aforementioned stops and controlling the extent of movement of said mechanism, and a type key mechanism including means to actuate said pivoted stop.

6. In a typewriting machine, a universal bar, a ribbon shifting mechanism including a rock shaft actuated from said bar, a lever on said shaft, a stop bar pivotally connected to said lever and an adjustable stop on said 130

stop bar; in combination with a pivoted spring retracted stop, a second lever secured to said rock shaft, a type actuating mechanism and a connection between said second lever and said type actuating mechanism controlling the position of said pivoted stop.

7. In a typewriting machine the combination with type levers, and a ribbon vibrating mechanism normally operating between a position of rest and normal printing position; of a fixed and an adjustable stop included in said vibrating mechanism, a platen shifting frame, a rocking axle on said frame, a stop movable into the path of either of the aforementioned stops, a lever arm secured

to said axle, and means, under the control of said frame and a type lever whose type prints above the normal printing line, to move said lever into the path of the adjustable stop and thereby cause an additional 20 movement of said ribbon mechanism to lift the ribbon above the normal printing line position.

In testimony whereof I have affixed my signature.

THEODOR EUGEN BUSCHMANN.
